HIGH FREQUENCY TELEGRAPH TRANSMITTER

Filed March 18, 1932

Fig. 1

Fig. 2

Circuit diagram showing two stages of a vacuum tube circuit. The top stage is a triode with grid bias R_1 and R_2 , plate load L , and plate voltage T . The bottom stage is a pentode with grid bias R_1 and R_2 , screen grid bias CR , and plate load L , with plate voltage T . The circuit includes coupling capacitors C_1 and C_2 and a common ground connection.

HIGH FREQUENCY TELEGRAPH
TRANSMITTER

Ernst Kramar, Berlin-Tempelhof, and Erich Lüttscher, Berlin-Friedrichsfelde, Germany, assignors to C. Lorenz Aktiengesellschaft, Berlin-Tempelhof, Germany, a company of Germany

Application March 18, 1932, Serial No. 599,738
In Germany March 31, 1931

2 Claims. (Cl. 250—8)

In the telegraphic keying of wireless transmitters, the signal impulses transmitted are rectangular in form since they are formed simply as interruptions of the carrier frequency. The rectangular form of the signals, however, gives rise to a large number of harmonic oscillations which easily interfere with other transmitters.

Therefore, in transmitters controlled from a separate oscillator, arrangements have been provided in the grid or anode circuits of the transmitter proper which prevent a rapid increase in the signal currents and ensure that signals fade but slowly to zero. This working may be called "rounded wave" keying. In these arrangements, the controlling oscillator remains permanently in operation, only the transmitter proper being keyed. The disadvantage of these arrangements, however, lies in the fact that duplex working is not possible, since the continuous operation of the associated controlling oscillator impairs the reception of the signals from the distant station.

This difficulty is overcome according to the present invention, by bringing the controlling oscillator into operation only when signals are to be transmitted. However, care must be taken that the transmitter is not connected until the controlling oscillator is oscillating at its correct frequency and that it is disconnected again before the controlling oscillator ceases to function. To this end, according to the invention, a switching arrangement operated by the keying device is provided.

In Figures 1 and 2, two forms of circuit arrangement which may be employed are illustrated, but the invention is not limited to this construction. In Fig. 1, St. represents the valve of the controlling oscillator and H the transmitter valve proper. Keying of the controlling oscillator is effected through contact r_2 of the relay R_2 and contact r_{12} of the relay R_1 , whilst the transmitter is controlled through the contact r_{13} of the relay R_1 . When keying the transmitter the following operations take place: As soon as the key T is closed the relay R_1 responds and closes contacts r_{11} , r_{12} and r_{13} . The relay is so adjusted that its contact r_{12} closes before its contacts r_{11} and r_{13} . The contact r_{12} closes the grid circuit of the controlling oscillator St. so that this valve operates and settles into oscillations of its normal operating frequency. A short time later the main transmitter is keyed by the contact r_{13} through an arrangement D in the grid circuit. The closure of contact r_{11} of relay R_1 completes an operating circuit for relay R_2 . This operating

circuit includes the key T. A condenser CR is connected in parallel with the relay R_2 . This relay now operates its contact r_2 which is connected in parallel with the contact r_{12} .

The arrangement of inductances and condensers D, which is connected in the grid circuit of the transmitter proper, ensures a slow rise of the voltage in the grid circuit and prevents a sudden fall of the voltage on switching off ("rounded wave" keying). Such an arrangement may also be provided in the anode circuit thereof. At the same time, the arrangement makes it possible for the controlling oscillator to attain its correct operating condition before the transmitter proper radiates its full energy.

On opening the key T the relay R_1 falls off first and switches off the transmitter through the contact r_{13} . The controlling oscillator is not affected by the opening of the contact r_{12} , since the grid circuit is still closed through the contact r_2 of the relay R_2 . Although the circuit for the relay R_2 is simultaneously broken by the contact r_{11} , this relay only falls off after a given time since the condenser CR is connected in parallel with it. The controlling oscillator is then also switched off by the contact r_2 when this opens.

A similar arrangement for keying the transmitter is illustrated in Fig. 2. In this arrangement, the transmitter is keyed by a reversing key. In the position of rest of the key T, the relay R_2 is energized and the contact r_2 , which is used for connecting the controlling oscillator, is open. When the key T is operated, the circuit for the relay R_2 is first broken at the left-hand contact of the key T and the controlling oscillator inserted through the contact r_2 . On fully depressing the key T, the relay R_1 is energized and switches in the transmitter through the contact r_1 . On opening the key T the same operation takes place in the reverse order. First of all, the circuit for the relay R_1 is broken and the transmitter switched off by the contact r_1 and then the relay R_2 is inserted and the controlling oscillator put out of operation by the contact r_2 .

According to the present invention, it is therefore possible to carry out satisfactory duplex working and at the same time to employ signals of rounded form so that harmonics and consequent interferences with other transmitters is avoided to the greatest possible extent.

Modifications may be made within the scope indicated by the appended claims, without departing from the spirit or sacrificing any of the advantages of this invention. For instance, the arrangement D, which serves to retard the rise

and fall of the signal current to its marking and spacing values, may be connected to the valve H in another way than shown.

What is claimed is:

- 5 1. In a high frequency telegraph transmitter, the combination of a transmitter circuit with a controlling oscillator circuit, a key for producing marking and spacing signals, means responsive to each operation of said key to marking positions 10 for switching on said oscillator before cutting in the transmitter circuit and to each operation of said key to spacing position for switching off the oscillator after cutting out the transmitter circuit, said means including relays, and a damping circuit disposed between one of said relays and 15 said transmitter circuit.

2. In a high frequency telegraph transmitter, the combination of a vacuum tube transmitter circuit with a vacuum tube oscillator circuit for controlling the transmitter circuit, a key for producing marking and spacing signals, means connected in the grid circuit of said transmitter for retarding the rise and fall of the signal current to its marking and spacing values, and means responsive to each operation of said key whereby for each marking signal the oscillator circuit is connected before the transmitter circuit is connected and for each spacing signal the oscillator circuit is disconnected after said transmitter circuit is opened.
